UNITED STATES PATENT OFFICE.

HELEN E. STROBHART, OF CHICAGO, ILLINOIS.

STRAINING DEVICE FOR SINKS AND THE LIKE.

1,145,938.

Specification of Letters Patent. Patented July 13, 1915.

Application filed January 14, 1915. Serial No. 2,182.

To all whom it may concern:

Be it known that I, HELEN E. STROBHART, a citizen of the United States, residing at Chicago, in the county of Cook and State of Illinois, have invented certain new and useful Improvements in Straining Devices for Sinks and the like; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to culinary devices and has for its object to provide a straining device to be used in connection with kitchen sinks and the like, and the invention has for its object to provide a novel arrangement and construction of straining device, which is maintained and secured in position above the sink or the like, so as not to interfere with the use of the sink.

A further object of the invention is to provide a straining device for the efficient straining of refuse which is consigned to the sink, so as to protect the sewerage system from an accumulation of grease and other matter which has a tendency to clog and stop up the same and interfere with the proper action thereof.

With these objects in view the invention consists in the novel construction of the straining device and particularly in the arrangement of the parts, which provides a sanitary device and which can be quickly removed or taken apart for cleaning, so that the device can be at all times maintained in a clean and sanitary condition.

Referring to the accompanying drawing—Figure 1 is a perspective view of the straining device constructed in accordance with this invention, and Fig. 2 is a vertical sectional view through the same and illustrating in fragmentary section the sink. Fig. 3 is a fragmentary plan view illustrating a construction for supporting the straining device away from the wall or the like, and Fig. 4 is a fragmentary view illustrating a cup or receptacle attached to the trough or guide.

Like numerals of reference indicate the same parts throughout the several figures, in which—

1 indicates the straining device, compris-

ing the flat back 2 and the rounded tapered front and side portion 3, the said back 2 being provided with perforations 4 for ready attachment of the device to a wall 60 or the like. The top edge of the rounded tapered portion 3 is bent outwardly to form a flange 5 which provides a means for handling the device, and which also acts as a stiffening means for the structure. Arranged on the front of the rounded portion 3 are two brackets 6 for the reception of a cleaning brush or the like, while the lower edge of the rounded tapered portion 3 is turned inwardly to form a flange 7 in the 70 manner as shown in Fig. 2.

Referring again to the back portion 2 it will be seen that the same extends downwardly to a point 8 below the terminus of the front portion 3. This depending portion 9 of the back 2 is provided transversely with a bead 10 and the portion 9 is free to spring slightly in relation to the back 2 proper of the device, while it will be seen that a projection 11 is pressed in the front 80 3 just above the flange 7 thereof.

12 indicates the perforated bottom which is provided with an encompassing flange 13 and a depending curved guide 14 provided along each side edge thereof with a flange 85 15. The said curved guide 14 being provided near its top with a transverse groove 16 to receive the bead 10 in the manner as shown in Fig. 2.

Having thus described the several parts 90 of this invention its operation is as follows: The device being attached and positioned in the manner as shown in the drawing the same can be quickly removed when desired, and the perforated bottom 12 can 95 be readily removed from the body of the device for cleaning. In assembling the device the perforated bottom 12 and its depending curved guide 14 is inserted from the top of the body portion and as it reaches 100 its normal position the curved depending guide 14 engages the bead 10 on the depending free portion 9 of the back 2 and springs it rearwardly until the said bead 10 enters the groove 16. At the same time the front 105 edge of the perforated bottom 12 passes the projection 11 in the front portion of the device and seats itself upon the flanges 5 thereof, thus securely holding the bottom 12 and guide 14 in proper position for quick 110 and ready removal.

It is apparent from inspection of Fig. 2

- that the bottom 12 and its guide 14 may be removed from the bottom of the device and attached from the bottom portion of the device instead of being inserted from the top thereof, by entering the front edge of the perforated bottom 12 between the projection 11 and the flange 7 and springing the rear portion of the perforated bottom 12 into position illustrated in Fig. 2.
- 10 In operation the straining device being attached as shown receives refuse therein allowing only the liquid portion thereof to pass through the perforated or screen bottom 12, from which it is guided by the guide 14 into the sink. The side flanges 15 of the guide 14 preventing the liquid from running over the edge of the guide 14, and at the same time adding to the stability of the same.
- 15 20 In some instances it may be required to support the straining device away from the wall and I can provide arms 17 formed in the manner as shown in Fig. 3, for properly positioning the straining device, and it may also be necessary by reason of the construction or location of the sink to employ a cup or receptacle 18 where it is not practical to have the trough or guide 14 deliver directly into the sink. In such an instance a

cup or receptacle 18 having a bail 19 which 30 may simply be held within a notch 20 cut in the manner as shown in Fig. 4, so as to receive liquid passing from the straining device.

Having thus fully described the invention it is of course apparent that certain changes and alterations may be made in the device, and I consider myself clearly entitled to all such changes and modifications as fall within the limit and scope of 40 the appended claim.

What I claim as new and desire to secure by Letters Patent of the United States is—

A straining device of the character described, comprising a receptacle having a 45 flat back and a depending free portion thereon, a front portion, a removable perforated bottom, a depending guide formed on said bottom and removable therewith, and means on said front and back for securing the said removable bottom and guide in normal operative position.

In testimony whereof, I affix my signature, in presence of two witnesses.

HELEN E. STROBHART.
